SHOE HEEL

Bernard F. Convy, St. Louis, Mo.

Application February 29, 1940, Serial No. 321,393

5 Claims. (Cl. 36—34)

This invention relates to shoe heels.

An object of the invention is to provide a shoe heel with novel ornamenting means.

Fig. 1 is a side elevation of a shoe heel embodying this invention;

Fig. 2 is a vertical section on line 2—2, Fig. 1;

Fig. 3 is a vertical section on line 3—3, Fig. 2; and

Figs. 4, 5 and 6 are side elevations of heels showing applications of the invention.

10 A shoe heel embodying this invention and, as specifically shown on the accompanying drawing, includes an opaque block 1, which may be of wood or its equivalent, formed in the shape of a heel with a concave heel seat 2, whereby it is adapted to be attached to a shoe upper in any conventional manner. The opaque block 1 has one or more orifices 3 extending therethrough from side to side. This orifice, or orifices, may be filled by an insert 4 fitting the orifice and having its ends 5 substantially flush with the sides of the block. The inserts 4, of light transmitting material, preferably polymethyl methacrylate, have all of their surfaces polished. The block 1 may have a pliable covering of leather, cloth, Celluloid or the like, indicated by the numeral 6, with edges 7 of the material turned in and secured to the wall of the orifices.

20 The orifice or orifices 3 may be cylindrical in form or may have a cross section other than circular. Such a different form is illustrated in Fig. 4, where the cross section is a trapezium. A cylindrical bore and cylindrical insert has some advantages in that such a bore can be cheaply and accurately made to correspond to stock cylindrical rods. In that case the inserts 4 may be cut from stock rods of the material. The inserts, of course, may be molded individually, or they may be cut and fashioned from block stock. Reference to Fig. 4 will indicate the possibilities 30 in the use of odd or irregular shapes for ornamental purposes.

40 Figs. 5 and 6 indicate the possibilities of the use of cylindrical inserts in connection with novel or unusual conformation of the breast of the heel. Fig. 5 indicates a heel which does not have a covering of pliable material. In this case the wood heel is finished by applying a lacquer to its surface. It will be understood also that the invention can be applied to shoe heels such as wedge heels, which depart even further from the conventional than the heels shown in Figs. 5 and 6.

50 Where a covering is used the block is preferably

reamed about the edges of the orifices, as best shown in Fig. 2, to receive the inturned edges 7 of the covering.

The inserts 4 are of light transmitting material, either transparent or translucent, and either colored or colorless. This material may be glass or a plastic, and of such materials polymethyl methacrylate, better known under the trade name "Lucite," is preferable because of its exceptional optical properties. By polishing the surfaces of 10 the inserts those surfaces adjacent the walls of the orifices form their own mirror, as viewed from the ends of the inserts. This enhances light reflection and transmission and obviates the necessity of providing any finish on the walls of 15 the orifices. This also obscures cement which may be used for fastening the inserts in place.

It will be obvious from the foregoing description that the invention accomplishes its objects.

I claim:

1. A shoe heel including an opaque block adapted to be attached to a shoe upper and having an orifice extending therethrough from side to side, and an insert of polymethyl methacrylate fitting said orifice with its ends substantially 25 flush with the sides of said block.

2. A shoe heel including an opaque block adapted to be attached to a shoe upper and having an orifice extending therethrough from side to side, and a transparent insert fitting said 30 orifice with its ends substantially flush with the sides of said block.

3. A shoe heel including an opaque block having an orifice extending therethrough from side to side, and a light transmitting insert fitting 35 said orifice with its ends substantially flush with the sides of said block.

4. A shoe heel including an opaque block adapted to be attached to a shoe upper and having an orifice extending therethrough, a covering of pliable material about the block with edges turned in and secured to the wall of the orifice, and a light transmitting insert fitting 40 said orifice with its ends substantially flush with the side of said block.

5. A shoe heel including an opaque block adapted to be attached to a shoe upper and having an orifice extending therethrough from side to side, and a transparent insert with all of its surfaces polished, fitting said orifice, and 50 its ends substantially flush with the sides of said block.

BERNARD F. CONVY.
